INVENTOR.

BY

Geo. P. Kimmel.
ATTORNEY.

UNITED STATES PATENT OFFICE.

JACOB DYKEMA, OF MUSKEGON, MICHIGAN.

WINDOW VENTILATOR.

Application filed April 15, 1922. Serial No. 552,971.

To all whom it may concern:

Be it known that I, JACOB DYKEMA, a citizen of the United States, residing at Muskegon, in the county of Muskegon and State of Michigan, have invented certain new and useful Improvements in Window Ventilators, of which the following is a specification.

This invention relates to improvements in window ventilators, and has for its object, to provide in a manner as hereinafter set forth, a window screen structure for use in connection as a sleeping or a bath room ventilator and which may be placed under the window sash to provide a screened air intake, and with the structure of the device so set up as to produce an indirect ventilator and to overcome a direct draft.

The invention is so free from the production of direct draft that a bed may be placed immediately in front of the window without danger of harm to the occupant of the bed and is of great value when used in a sick room or in other like location.

In accordance with the invention, the indirect-draft screen is arranged to occupy only the lower portion of the window, while the upper portion of the window is occupied by the window sash elevated to permit the location of the window screen at a relatively low point.

The window screen itself is intermediate hinged so that it may be placed in the window sash between the usual window beads, and in order to permit the window screen to be applied to and removed readily, such screen is so constructed as to prevent any direct draft upon the sleeper.

In accordance with the invention, the deflecting structure when turned on its intermediate hinge into an alined position fits between the sash beads and is then extended so as to occupy the space usually occupied by the sash and will readily hold its position without danger of slipping from the lodged position in the window casing.

The inner face of the removable ventilator deflecting structure, is in the form of a triangular structure, into which air may readily enter from the outside of the window, but the screen portion of the structure will prevent the entrance of any insect or the like into the room, wherefore no annoyance is caused to the occupant of the room.

The invention will be best understood

from a consideration of the following detailed description taken in connection with the accompanying drawings forming part of this specification, with the understanding that the invention is not confined to any strict conformity with the showing of the drawings, but may be changed and modified so long as such changes and modifications mark no material departure from the salient features of the invention as expressed in the appended claim.

In the drawings:—

Figure 1 is a perspective view of the lower portion of a window sash with the invention applied.

Fig. 2 is a section on the line 2—2 of Fig. 1.

Fig. 3 is an out-of-door elevation of the structure shown in Fig. 1.

Fig. 4 is a section on the line 4—4 of Fig. 2.

Referring to the drawings, there is shown a window frame 1, which may be of ordinary construction and therefore requires no specific description.

The window frame is shown as provided with sash beads 2 to which are fitted frames 3, which may be joined end to end by hinges 4 or otherwise, together forming a frame structure long enough to extend from one side to the other of the structure made up of the hinged frames 3.

That portion of the frame 3 presented toward the outside of the window frame is provided with border moldings 5, so arranged as to hold wire netting 6 in each frame carrying the screen 6.

The two frames 3 are held together by the hinges 4 and when the frames are in alinement, the frames 3 extend from end to end of the window sash and have tongues 7 at the outer ends entering between the molding 2, so that under ordinary conditions of use, the frames 3 may be made to hold their position in the window sash without liability of escaping therefrom.

By disaligning the frames 3 and breaking their alinement at the hinges 4, the joined frames may be introduced into the window frame or removed therefrom at the will of an operator.

When the twin frames are placed in the window frame and straighten out, they will effectively resist displacement, and no ordinary forces to which the hinged frames may be subjected will affect them.

2
What is claimed is:—

A non-draft window screen comprising a pair of frames of substantially triangular cross section with the broad face covered with screen mesh and hinged together at the meeting ends, and of a combined length to lock in alignment between the sash beads of

a window frame the ends of the frames being open to the exterior atmosphere, the angularly disposed faces of the frame being imperforate.

In testimony whereof, I affix my signature hereto.

JACOB DYKEMA.
